DRAFT REGULATOR FOR ORCHARD
HEATERS

William C. Scheu, Upland, Calif.; Henrietta Scheu, W. Leland Scheu, and C. H. Dekker, executors of said William C. Scheu, deceased, assignors to Scheu Products Company, Ltd., a corporation of California

Application December 18, 1940, Serial No. 370,615

1 Claim. (Cl. 158—91)

This invention relates to temperature-controlled draft regulators for liquid fuel orchard heaters and is concerned particularly with heat-responsive devices for automatically establishing a controlled influx of combustion air to the fuel vaporizing chamber of such a heater for normal burning operation thereof following the starting or ignition period of such a heater.

Without being necessarily limited thereto, the heat-responsive draft-regulating device of this invention is primarily adapted for use with vaporizing type liquid fuel orchard heaters. In heaters of this type a vaporizing flame is maintained at or near the surface of the body of fuel contained in the heater to cause vaporization from the surface of this fuel. The oil vapors pass upwardly into a stack where additional air is mixed with them to cause substantially complete combustion of the vapors in a main flame at a point removed from the vaporizing flame. A heater of this general type provided with such a stack forming a main combustion chamber is shown in my U. S. Patent No. 1,930,863, issued October 17, 1933.

Heaters of this type are provided with one or more air-admitting openings in the body communicating with the vaporizing chamber to admit air to the vaporizing flame in the vaporizing chamber. With such arrangement it is preferable to supply a relatively large quantity of air to the vaporizing chamber to support the vaporizing flame when the heater is first ignited and until the vaporizing chamber has been heated. After the vaporizing chamber has become heated and the main combustion flame is well established, a smaller amount of heat from the vaporizing flame is required to vaporize fuel; and if the air supply is not reduced to diminish the flame, there will be a tendency to vaporize an excess quantity of fuel. These relations are all a function of the heat generated in the vaporizing chamber and are substantially independent of the temperatures existing where the main combustion takes place in the stack, or at any other place removed from the vaporizing flame.

In order to obtain proper and satisfactory operation of such a liquid fuel heater it is desirable to restrict the flow of air admitted to the vaporizing chamber after a sufficient quantity of heat has been generated therein. In many cases this operation is performed manually or not at all due to the labor involved. When this operation is not performed the heater consumes an excess quantity of fuel and often smokes badly, thus wasting fuel.

The principal object of the invention is to provide a heat-controlled draft-regulating device for use in connection with a vaporizing type of liquid fuel orchard heater, which is operable to provide a substantially unrestricted inflow of air into the vaporizing chamber during a preliminary ignition period and to restrict automatically the admission of air to said vaporizing chamber when the ignition is completed, in response to a temperature increase resulting from the heat generated within the heater, so as to thereafter maintain the relatively restricted admission of air to the chamber in quantities sufficient to maintain the desired normal burning rate during subsequent operation of the heater.

A further object of the invention is to provide a heat-responsive draft-regulating device for use in association with a vaporizing type liquid fuel orchard heater, which is rugged, simple in operation and construction, and which may be readily removed for repair or for transfer to another heater where it may be readily installed.

Further objects and advantages of the invention, of which the above are typical, will become apparent as the description proceeds.

The draft-regulating device of my invention may comprise a regulating plate adapted to be pivotally mounted adjacent the air-admitting opening of a liquid fuel orchard heater. The draft-regulating plate is movable between a first position affording relatively free passage of air through the opening and a second position restricting the passage of air through the opening. A bimetallic thermostatic element is provided which is operatively associated with the plate and is disposed in heat-receiving relation to the heater and is operable in response to heat generated in the heater to cause the plate to move from its first position to its second position.

How the above, as well as other objects and advantages of my invention are attained will be more readily understood by reference to the following description and the annexed drawing, in which:

Fig. 1 is a vertical section through the bowl of an orchard heater showing my improved draft-regulating plate mounted on the bowl cover;

Fig. 2 is an enlarged fragmentary vertical section on line 2—2 of Fig. 1, showing the draft-regulating cap open in full lines and closed in dot-dash lines; and

Fig. 3 is a fragmentary vertical section on line 3—3 of Fig. 2.

There is shown in Figs. 1 to 3 of the drawing a portion of a standard type of vaporizing liquid

fuel orchard heater, indicated generally at 10. The orchard heater comprises a bowl 11 which not only provides a base for supporting the upper structure but also forms a reservoir that contains a body of liquid fuel 12 which is vaporized in bowl 11 and burned in the heater stack. Bowl 11 is provided with a cover 14 which has a centrally disposed collar portion 14a around which the lower end of stack 15 fits snugly. The stack may be of any type suitable for orchard heaters, the exact kind being immaterial as far as the present invention is concerned.

The space 16 above the fuel body 12 and enclosed by the walls of bowl 11 and cover 14 constitutes a vaporizing chamber. A suitable opening defined by the raised collar portion 17 of cover 14 is provided in order to admit air to the vaporizing chamber for maintenance of the vaporizing flame therein. A draft tube or flame-stabilizing baffle 18 is preferably provided to facilitate the maintenance of a vaporizing flame within chamber 16. The upper end of draft tube 18 is preferably provided with an outwardly extending flange which engages the inwardly turned flange on raised collar 17, as shown in Fig. 3, to support the draft tube, which extends downwardly from cover 14 into the oil body 12 as illustrated in Fig. 1. The upper end 20 of draft tube 18 is open for the admission of air which enters the vaporizing chamber through the draft tube. A suitable wick 19 is preferably provided adjacent the upper end of tube 18, the wick member taking any suitable form, such as the body indicated, and is preferably of fibrous asbestos or other porous material. The wick is preferably wrapped or enclosed in a foraminous metal envelope, not shown, which holds the wick in place and yet permits access of oil to the lower portion of the wick.

The draft-regulating device is shown as comprising a draft-regulating plate 94 pivotally mounted on the cover 14 of the heater adjacent the air-admitting opening defined by the raised collar 17 and draft tube 18, as by means of hinge 95. Plate 94 is movable about hinge 95 between the first, or air-admitting position, shown in Fig. 2 in full lines, and the second, or air-restricting position, shown in Fig. 2 in dot-dash lines. The plate in moving between the first and second position passes through an intermediate position in which the center of gravity of the assembly is in a vertical plane passing through the hinge axis; and the plate is gravity biased toward the first position when it is between the first and intermediate positions, and is gravity biased toward the second position when the second and intermediate positions.

A portion of said plate, such as a tab member 96, extends away from said hinge and is so positioned as to be engageable by a pin member 90 and so formed as to have its outer end 97 rest against the cover 14 as indicated in full lines in Fig. 2.

The pin member 90 extends upwardly above the cover 14 through a suitable slot or opening 100 provided therein. The pin member is rigidly secured to a bimetallic thermostat bar 91 mounted in a suitable case 92 secured to the underside of cover 14 of the heater in any suitable manner, as by bolts 93.

The center of gravity of the assembly comprising regulating plate 94, the tab member 96 and associated parts adapted to swing about the hinge 95, is to the left, as viewed in Fig. 2, of a vertical line extending through the axis of hinge

95 when the outer end 97 of tab member 96 is in engagement with the cover 14, so that a tilted position of the plate member for providing substantially free access of air to the heater may be maintained by the action of gravity.

The plate 94 is preferably provided with one or more air-admitting openings 98, and an adjustable disk 99, provided with an adjusting handle 102, is preferably mounted on plate 94. The disk 99 is preferably rotatably mounted on the plate 94 at the center thereof, as through the agency of a spring-tensioned loose rivet 103 or the like. Disk 99 has a slot or opening 101 which is movable into and out of registration with the openings 98, through the agency of the handle member 102, in order to cover more or less of the openings 98 and so impose more or less restriction on air passing through openings 98 to the heater interior when the plate 94 is lowered, as shown by dot-dash lines in Fig. 2.

When a heater provided with this embodiment of the device is lighted, the thermostat is cold and the thermostat and the opened draft-regulating plate occupy positions shown in full lines in Figs. 2 and 3. After the heater has been ignited, the flame from the vaporizing chamber plays against or radiates heat to the case 92 and the contained thermostat 91 gradually rises in temperature and bends upwardly. Movement of bimetallic element 91 causes pin 90 to engage and raise tab member 96, tipping the plate member 94 forward about the hinge 95 until the center of gravity of the plate and associated parts is moved to the right of the aforesaid vertical line. The plate member 94 is then biased toward a draft-regulating position by gravity, independently of further movement of the pin member 90, and falls freely down to its second or draft-regulating position as is indicated in dot-dash lines in Fig. 2 and in full lines in Fig. 1. The draft regulating plate 94 may be formed as a cap-shaped member so that the outer edges of said cap may engage the shoulders 17 when said plate is in draft regulating position as above described.

Upon being moved to and through the intermediate position the gravity bias toward the second position allows the plate to fall freely with the aid of gravity to the second position restricting the passage of air through the opening.

In its preferred form the plate is so proportioned that its center of gravity is located above the pivotal or hinge axis and is shiftable by movement of the plate between its first and second positions, from a position in which a moment is produced urging the plate toward its first position to a position in which a moment is produced urging the plate toward its second position. The moments are such that when the plate is in the first or second position it is urged respectively toward the first and second positions. The action of the thermostatic element is to cause movement of the plate from the first position against this moment to a position in which the center of gravity has shifted sufficiently to produce sufficient moment to cause movement of the plate to the second position irrespective of further movement of the thermostatic element.

Having described my invention, it will be understood that various changes in the shape, construction, and arrangement of the various parts may be made without departing from the spirit and scope of my invention; and consequently it is desired that the foregoing disclosure be considered as illustrative of, rather than limitative

upon, the invention set forth in the appended claim.

I claim:

In association with a fuel bowl cover for an orchard heater provided with an air-admitting opening, a heat-responsive draft-regulating device which comprises: a draft-regulating plate hinged to said cover adjacent said opening, said plate being movable on the hinge between a first position affording relatively free passage of air through said opening and a second position restricting the passage of air through said opening, the center of gravity of said plate being located above the hinge and being shiftable by movement of said plate from its first position toward its second position, from a position in which a mo-

ment is produced urging the plate toward its first position to a position in which a moment is produced urging said plate toward said second position, said plate including a portion extending outwardly from the plane thereof; a bimetallic element carried on the underside of said cover and having an end adapted to move upwardly in response to heat; and a member secured to said end and extending through said cover, said member being adapted to engage said portion when said plate is in its first position and move said plate to shift its center of gravity to a position in which a moment is produced urging said plate toward its second position.

WILLIAM C. SCHEU.
